CLAIM

The ornamental design for a plate dish as shown and described.

DESCRIPTION

1. Plate Dish

FIG. 1.1 is a perspective view of a plate dish showing my new design; and

FIG. 1.2 is a top view thereof.

The broken lines in the reproductions represent the boundary of the claimed design and the de-emphasized or half-toned portion represents an unclaimed portion that forms no part of the claimed design.

1 Claim, 2 Drawing Sheets
